UNITED STATES PATENT OFFICE.

ARTHUR L. HALLIDAY, OF NEW YORK, N. Y., ASSIGNOR TO MATTHEW J. WHITTALL, OF WORCESTER, MASSACHUSETTS.

DESIGN FOR CARPET.

SPECIFICATION forming part of **Design No. 24,937**, dated **November 26, 1895**.

Application filed **October 26, 1895**. Serial No. **566,933**. Term of patent **3½ years**.

To all whom it may concern:

Be it known that I, ARTHUR L. HALLIDAY, residing at 42 West Twenty-second street, city and county of New York, State of New York, have invented and produced a new and original Design for a Pattern to be Wrought into Carpet, in such coloring as may be designed; and I do hereby declare that the drawing accompanying this specification gives and conveys to any one skilled in the art of carpet weaving and manufacture a clear understanding of the same, and is sufficient to enable such person to use my invention.

The design consists of the body A and the border B.

The body A is decorated with clusters of mosswork of different size and grouping.

The border B shows a large continuous group of the moss with a narrow band of similar work on its inner edge and smaller groups ²⁰ toward the outer edge.

What I claim as my invention, and desire to secure by Letters Patent, is—

1. In a design for a carpet, the body A, substantially as shown.
2. In a design for a carpet, the border B, substantially as shown.
3. The design for carpets, consisting of the body A, and the border B, substantially as shown.

ARTHUR L. HALLIDAY.
